UNITED STATES PATENT OFFICE

ANNA E. SJOSTRAND, OF ST. PETER, MINNESOTA

EAR PROTECTOR

Application filed November 24, 1930. Serial No. 497,917.

This invention appertains to toilet articles and more particularly to a novel device for use in beauty parlors for protecting the ears during the various operations of hair dressing.

Considerable injury and discomfort is often caused to persons having their hair dressed from irons and the like, and also from the hot blast of air used in the hair drying operation.

It is therefore one of the primary objects of my invention to provide a device for snugly fitting over the ears, which will effectively protect the ears from heat, so as to give the persons having their hair dressed perfect safety and comfort during the hair dressing operation.

Another salient object of my invention is the provision of novel means for forming the ear protectors, so as to render the same comfortable to the wearer and attractive to the eye.

A further object of my invention is to provide a protector for the ears of persons having their hair dressed embodying novel cup-shaped members snugly fitting over the ears formed of asbestos or like material, suitably reinforced with chin straps connected to the reinforcing members and adjustably united.

A still further object of my invention is to provide an improved ear protector of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a side elevation showing the device in use.

Figure 2 is a front elevation of my improved ear protectors with one of the ear cups shown broken away and in section.

Figure 3 is a detail section taken on the line 3—3 of Figure 2 looking in the direction of the arrows.

Referring to the drawings in detail, where-

in similar reference characters designate corresponding parts throughout the several views, the letter A generally indicates my improved ear protecting device, which comprises a pair of substantially cup-shaped ear receiving members 5 and 6. These ear receiving members 5 and 6 are preferably molded from asbestos fibre or like material 7, reinforced by metallic bands 8. These metallic bands 8 are provided with, at spaced points, headed knobs 9, which form anchoring means for the asbestos material. In actual practice the asbestos paste material 7 can be pressed over the metal reinforcing members 8 and 9 and molded into shape. These metal bands 8 extend downwardly and inwardly from the ear receiving members 5 and 6 to form chin engaging resilient straps 10, the lower terminals of which are arranged in overlapping relation and connected together by an adjustable sleeve or loop 11.

The inner surface of the inner cups or members 5 and 6 can be coated with or receive a lining of some soft material, such as rubber or the like 12.

I also prefer to finish the outer surface of the ear cups or members 5 and 6 so that the same will present a pleasing and attractive appearance. The ear cups or members 5 and 6 are provided with an exterior skin 12' of smooth washable material.

It is to be noted that the upper end of the ear cups or members are provided with depending flanges 13, which act as hooks for engaging over the ears, and these cups are so formed as to conform to the actual configuration of the ear as nearly as possible.

From the foregoing description, it can be seen that I have provided novel means for guarding the ears during the hair dressing operation, and which means is so constructed as to permit the ready association thereof to the ears and with a maximum amount of comfort.

Changes in details may be made without departing from the spirit or the scope of this invention, but:

What I claim as new is:

1. An ear protecting device for hair dressing parlors, comprising a pair of like ear

receiving cups, each comprising a metallic reinforcing band having a plurality of spaced headed knobs thereon, a body formed of heat insulating material pressed over the bands and headed knobs, resilient chin strap extensions formed on the metallic bands, and a sleeve adjustably connecting said extensions together.

2. An ear protecting device for hair dressing parlors, comprising a pair of like ear receiving cups, each comprising a metallic reinforcing band having a plurality of spaced headed knobs thereon, a body formed of heat insulating material pressed over the bands and headed knobs, resilient chin strap extensions formed on the metallic bands, a sleeve adjustably connecting said extensions together, and a lining of cushioning material on the inner face of each of said ear receiving members.

3. A device for protecting the ears in hair dressing parlors comprising a pair of like ear receiving members, each including a body of heat insulating material, a lining of cushioning material and an exterior skin of smooth washable material.

4. A device for protecting the ears in hair dressing parlors comprising a pair of like ear receiving members, each including a body of heat insulating material, a lining of cushioning material and an exterior skin of smooth washable material, and means for reinforcing the body.

In testimony whereof I affix my signature.

ANNA E. SJOSTRAND.
